CLAIM

The ornamental design for a construction anchor, as shown and described.

DESCRIPTION

FIG. 1 is a front angled isometric view of the construction anchor.

FIG. 2 is a front view of the construction anchor.

FIG. 3 is a side view of the construction anchor, it being understood that the opposite side is a mirror image thereof.

FIG. 4 is a back view of the construction anchor.

FIG. 5 is a top view of the construction anchor; and,

FIG. 6 is a bottom view of the construction anchor.

The broken line portions shown in FIGS. 1 through 6 illustrate environmental subject matter only and form no part of the claimed design.

1 Claim, 6 Drawing Sheets

FIG. 2

FIG. 3

FIG. 4

FIG. 5

FIG. 6
